BERNARD J. PAULSON
Inventor
Young, Young
Attorney

UNITED STATES PATENT OFFICE.

BERNARD J. PAULSON, OF RACINE, WISCONSIN.

GAME APPARATUS.

Application filed August 20, 1923. Serial No. 658,342.

To all whom it may concern:

Be it known that I, BERNARD J. PAULSON, a citizen of the United States, and resident of Racine, in the county of Racine and State 5 of Wisconsin, have invented certain new and useful Improvements in Game Apparatus; and I do hereby declare that the following is a full, clear, and exact description thereof.

10 My invention relates to improvements in games and is particularly directed to that class having a rotatable device for directing certain plays or movements.

It is the object of my invention to provide 15 a game having a rotatable device which indicates the movement of certain markers upon a map to direct vehicles, particularly motor vehicles, over highways, and the object of the game residing in the distance 20 travelled under certain conditions.

Another object of my invention is to provide a game having all the various phases for motoring, the same being controlled by a movable member.

25 In the accompanying drawings:—

Figure 1 is a top plan view of a receptacle having mounted therein an indicating member for directing the movement of certain markers, equivalent to motor vehicles, over 30 a predetermined section of a map.

Figure 2 is a sectional view taken on the line 2—2 of Figure 1, showing the indicating member provided with various markings.

35 Figure 3 is a sectional view taken on the line 3—3 of Figure 2.

Figure 4 is a map section showing thereon a certain route to be travelled over.

Figure 5 shows one form of markers 40 adapted to indicate the positions of players upon the map, while

Figures 6 and 7 disclose in general the type of score card used in connection with the game.

45 Referring to the accompanying drawings in detail, wherein like reference characters denote corresponding parts throughout the several views, the numeral 1 designates an oblong receptacle, formed of some suitable 50 material, preferably wood, and having mounted therein my improved indicating member, to be hereinafter described.

As disclosed in Figure 2, the walls 2 of the receptacle have their upper edges provided with a tongue and groove structure adapted 55 to receive thereon the side walls 3 of a top 4.

The end walls of the receptacle 1 have their intermediate portions cut out, as indicated at 5 to receive therein the trunnions 60 6 formed on the end portions of a cylinder 7, upon the periphery of which a facing 8 having thereon various directions of the game is placed. The top 4 also has its end 65 walls provided with similar cut out portions which are adapted to fit down upon the trunnions 6 and hold the same in place.

In order to rotate the cylinder 7, within the receptacle 1, one of the trunnions 6 has made integral therewith a turning knob 9. 70

The top wall of the closure 4 has extending longitudinal thereof a plurality of spaced openings 10, 11, 12, 13 and 14 so that markings carried by the cylinder 7 may be readable therethrough. As disclosed in the 75 drawings these openings have their sides beveled for maximum visibility of markings on the cylinder 7, and each have carried thereon certain captions under which the various markings carried by the cylinder 80 fall.

As disclosed in Figure 1 of the drawings I have provided means for closing the opening 10, the purpose of which will herein-after be apparent, and this means consists 85 of a transverse metallic strip 15 projecting through the side walls of the closure and having its end portions bent at right angles to form suitable finger portion 16. It will be noted that this strip is positioned under 90 the space between the first and second openings, thus preventing the same from obstructing the view therethrough. After a certain part of the game, hereinafter to be described, has been played it is desirous to close the first opening, that giving the various cars used, and in order to accomplish this I have formed integral with the strip 15 an extension 17, which is moved into 95 such a position as to close the first opening 100 by the movement of the strip 15.

In a like manner certain of the remaining openings, the last two, (13 and 14) are closed at various times and in order to effect

this I have provided a second transverse strip 18 having the finger portions 19 and the closing members 20 and 21 which are moved into and out of closing positions with 5 respect to the last two openings.

Having thus fully described the structure of my improved game apparatus I will now endeavor to illustrate how the same is played. Having selected a map having 10 thereon the route to be travelled, the players, two in number, then rotate the cylinder to determine what particular make of car they shall use; for instance, one rotates the cylinder and the name Cadillac appears 15 under the first opening; he then uses this car throughout the trip, entering the name on his record card, provided for tabulating the various plays and to facilitate totaling the scores. In a like manner his opponent selects his car, after which the strip 15 is 20 moved in such a direction to cause the opening 10 to be closed during the progress of the game, this being done to avoid confusion in reading the captions registered by the 25 cylinder 7, under the other openings 11, 12, 13 and 14.

Referring to Figure 4 and assuming that the route to be travelled by the players is from Madison to Kilburn, the game is now 30 started and the first player by grasping the knob 9 rotates the cylinder and notes under the head "Luck O'er the Road" the instructions appearing upon the cylinder, we will assume that the instructions are "Good 35 Road—drive to next town." The player then observes the map and notes the distance between Madison and Middletown which is 8 miles. Under the head "Miles Travelled" the word "Count" appears and under 40 "Driving Time" appears "30 miles pr. hr.", while under the last head "Elapsed Time" appears the word "Same."

In putting down this score the player has noted that the distance from Madison to 45 Middletown is 8 miles and if he travelled this distance at the rate of 30 miles per hour it will require, according to the table which I have provided on the score cards accompanying the game, 16 minutes to travel this 50 distance.

This time is entered upon his card under the head "Driving Time" and "Elapsed Time." After one player has rotated the cylinder the other does likewise and notes 55 the instructions appearing under the openings of the closure.

In some cases it may be that the player is detained and this I add to his score as noted by the notation appearing under the head 60 "Elapsed Time."

This continues until the routes selected by the players have been covered and then by the rules of the game the score is added and the winner determined, an example of which 65 is hereinafter pointed out.

In this form of the game I have described a somewhat more advanced form, and when the game is played by children it is the intention to close the first, and last openings thus leaving the "Luck O'er the Road" and the "Miles Travelled," the object of the game being to reach a given point in the least number of spins of the cylinder. 70

The position of the vehicles upon the map is indicated by suitable markers 22, of various colors, similar to that disclosed in Figure 5 of the drawings. 75

It is of course to be understood that this game may be adapted to other forms of travel besides motor travel, by changing the reading matter on the face of the cylinder and by substituting a different top, or changing the captions over the openings. For instance, it may be adapted to travel by boat, 80 rail, train, or hiking and in each case the object of the game being to make the same as true to life as possible, and filled with interesting incidents over the route travelled. 85

It is also my desire to provide a number 90 of maps showing thereon routes over various portions of the country, together with data of interest to the tourist. The maps are printed with the mileage indicated between points, such as that disclosed in the drawings, upon which I have indicated the same by the lines appearing across the route, this mileage being indicated in easily computable units. 95

In playing this game, each player should 100 have two markers, so that one marker may be left in the position determined by the previous play, while the other marker is moved forward, counting from the place occupied by the first marker, as in playing "cribbage."

Although several ways are employed in 105 keeping this score, I will describe herewith two of the most preferable schemes which I have so far devised. With one of these schemes the following order is observed in totaling the score, such as that appearing, 110 for instance, on the score card Figure 6:

Credit of 10 points per mile for distance travelled.

Credit of 1 point per minute for driving time. 115

Penalty of 1 point per minute for elapsed time above driving time total (to be deducted from grand total).

Credit of 10 points per minute for safety and courtesy stops, such as stopping for railroad crossing, putting on chains when encountering wet roads, stopping to put oil in crank case, stopping to help motorist in distress, etc. 120

Credit of 5 points per minute for all pleasure stops made, such as "stopping 10 minutes to admire view," stopping at lake to fish, stopping at points of interest, such as The Dells, Devils Lake, etc., all these 125 points of interest being shown on map, with 130

a legend specifying length of time motorist should stop in order to see the place advantageously.

Penalty of 10 points per minute for all 5 trouble stops, such as punctures, blowouts, broken spring, radiator boiling, etc.

Although this manner, as previously described, of keeping the score is perhaps the most attractive, there is, however, a simpler 10 way in which this may be done, as follows:—

40% for best driving time.

35% for best mileage.

10% for the greatest amount of pleasure on trip.

15 5% for shortest elapsed time.

5% for safe driving and road courtesy.

5% for least trouble on trip.

It will be seen, therefore, that although one player may cover the distance between 20 two points in a shorter period of time than the competing player, nevertheless the latter may win the game by greater mileage, more pleasure, safer driving, and less road trouble. In fact it frequently happens that by 25 taking a route with the most attractions on it, the game can be won, with a fair amount of luck, by using good judgment, beating the player who takes the short, direct route without scenic or pleasure attractions. Obviously, therefore, this adds to the interest 30 of the game.

It will thus be seen that a game has been provided, which holds the interest of the 35 player throughout the entire period of playing, which is adapted not only to children's use, but also to those of more mature years, and which may be varied so that a gradually

increasing number of conditions are imposed upon the player, as pointed out above, so that it may be equally attractive for 40 grown people.

Although the invention has been described in considerable detail, it is to be understood that it may be variously embodied and is therefore to be limited only as claimed. 45

Having thus fully described my invention, what I claim as new, and desire to secure by Letters Patent, is:—

1. A game of the class described comprising a receptacle, a drum mounted for rotation within said receptacle, instructions of different characters arranged in rows upon the periphery of said drum, openings arranged within the top wall of said receptacle for viewing each of said rows, a bar 50 slidable transversely of said top wall, and extensions carried by said bar for closing certain of said openings.

2. A game of the class described comprising a receptacle, a drum mounted for rotation within said receptacle, instructions of different characters arranged in rows upon the periphery of said drum, openings arranged within the top wall of said receptacle for viewing each of said rows, bars 55 slidable transversely of said top wall and having fixed thereto extensions for closing certain of said openings, and one bar adapted to be operated after the initial turn of said drum.

In testimony that I claim the foregoing I have hereunto set my hand at Racine, in the county of Racine and State of Wisconsin.

BERNARD J. PAULSON.
